ABSTRACT OF THE DISCLOSURE

In the weaving of cloth on a loom in which the weft threads are pulled through the shed from a supply bobbin outside the shed, a selvage is formed by a method in which a tuck-in needle is subjected to a reciprocating arcuate motion generally transversely of the warps and a reciprocating linear or substantially linear motion generally lengthwise of the warps, these motions being superposed. The arcuate motion includes a positive acceleration of the needle back toward the shed from an extreme position in which the weft-grasping hook on the needle is laterally outside the shed but vertically between the upper and lower halves of the shed, a deceleration which retards the passage of the weft-holding hook across the selvage portion of the width of the web of cloth, and a reacceleration toward an inner rest position in which the needle is retracted out of the shed and out of the way of the reed. Separate cams produce the arcuate and linear motions which are superposed on each other, the latter motion also including a pause timed to bring the needle briefly to rest as regards both motions while the hook is within the selvage portion of the width of the cloth being woven. A third cam suitably coupled to those already mentioned effects reciprocating motion, lengthwise of the warps, of a weft thread clamp adjacent the edge of the cloth between the line of picking and a position making it possible for the tuck-in needle to grasp the weft last picked through the shed. A fourth cam moves the clamp up and down.

The present application pertains to subject matter related to that disclosed and claimed in my copending application Ser. No. 641,664, filed May 26, 1967.

BACKGROUND OF THE INVENTION

The present invention relates to looms of the kind in which the weft supply bobbin remains outside the shed and, more particularly, to the formation of selvages on cloth woven on such looms by tucking into the shed the ends of the weft threads. The invention provides a method of forming such selvages, and apparatus by means of which that method may be practiced.

It has heretofore been proposed to form selvages on cloth woven on looms of the type above described by means of a selvage tuck-in needle which, while tucking in the end of the weft, is continuously accelerated, moved into the shed and brought to an inoperative stationary position of rest. This has the disadvantage that the weft end which is to be tucked in becomes disengaged from the tuck-in needle at a relatively early phase in the process of shed closing by means of which the weft end is to be bound into the cloth. If the shed, which changes during tucking in, is not closed far enough when the weft end becomes disengaged from the needle, the weft end may spring out of the shed, particularly if it is made of a synthetic, relatively resilient yarn which exhibits a degree of springiness. The selvage, if formed at all, is defective. Some or all of the warp threads in the selvage region are

2

not bound in. The object of the invention is to improve the operating method and loom in this respect.

SUMMARY OF THE INVENTION

According to one aspect of the present invention, in a method of operating a loom of the kind specified, the selvage tuck-in needle in its pivotal movement between the yarn-receiving stationary position and the inoperative stationary position is first accelerated, then temporarily retarded in the region of the selvage, reaccelerated and then brought into the inoperative stationary position. According to another aspect of the invention, a loom of the kind specified has a drive which is arranged to impart to the selvage tuck-in needle a pivotal movement between the 15 yarn receiving stationary position and the inoperative stationary position in which movement the tuck-in needle is first accelerated, then temporarily retarded in the region of the selvage, reaccelerated and then brought into the inoperative stationary position.

Because of the temporary lag provided by the invention in the pivotal movement of the selvage tuck-in needle while it is tucking the weft end in, the shed is further closed than heretofore before the end which is to be tucked in leaves the needle. As the weft end leaves the 25 hook of the needle, it can then cling sufficiently to the warp threads not to spring back out of the shed. Since however the start of the pivotal movement of the needle need be no later than in prior art practice, the space at the edge of the cloth is, as before, clear early enough for the return movement (in the direction of the warp) of a selvage thread clamp which grips the weft end immediately after picking. This is important because, immediately the selvage thread clamp has surrendered the weft end to the tuck-in needle, it must return in the direction of the 30 warp to grip the next weft in the picking line.

BRIEF DESCRIPTION OF THE DRAWING

The invention will now be further described with reference to the accompanying drawing in which:

FIG. 1 is a view in elevation of a loom, seen from the cloth end, into which the invention may be embodied and on which the invention may be practiced;

FIG. 2 is a plan view on a larger scale, illustrating the movement of a tuck-in needle in the loom shown in FIG. 1;

FIGS. 3 to 6 illustrate other positions of the needle shown in FIG. 2;

FIG. 7 is a fragmentary vertical section through the 50 loom shown in FIG. 1 along a plane parallel to the warps and illustrating one of the tuck-in needles and weft thread clamps thereof, together with driving mechanism for those elements;

FIG. 8 is a diagrammatic plan view of the tuck-in needle of FIG. 7, showing the mechanism which imposes an angular motion thereon;

FIG. 9 is a developed view of the profile of the cam 57 shown in FIG. 8; and

FIGS. 10 to 13 are four diagrams illustrating operation 60 of the loom.

DESCRIPTION OF THE PREFERRED EMBODIMENT

The loom shown in FIG. 1 comprises two upright side frames 1 and 2 connected by a central cross member. Between the side frames there are disposed a warp beam 17, heddle frames 9, a reed 8 and a cloth beam consisting of two portions 3 and 18. The side frame 2 carries a picking motion 13. From this picking motion shuttles 12 move through the shed along a shuttle guide 14, picking through the shed on each travel a weft 10 drawn off a supply bobbin 11 which remains outside the shed. Each

shuttle 12 goes to a catching motion 15 on the side frame 1.

On the left in FIG. 1 there is a driving motor 7, from which power is transmitted by a flywheel 6 to a main drive shaft 5 for the loom. This main shaft 5 drives the moving parts of the loom, e.g. the heddle frames 9, the reed 8, the picking motion 13 and catching motion 15.

A selvage tuck-in device 16 is associated with each of the motions 13 and 15. A corresponding tuck-in device 21 for the dividing selvage in the middle of the loom is mounted on a rod 20. The devices 16 and 21, more fully described below, tuck the ends of each weft picked through the shed 88 (FIG. 7) into the next shed, so that selvages are formed at the edges of the cloth webs 4 and 19 (FIG. 1).

Each of the selvage tuck-in devices 16 and 21 includes a tuck-in needle 23 with a hook 22 at the end thereof (FIGS. 2 to 6). The movement of the needle is shown in detail in FIG. 2. Point A is the point in the hook which is occupied by a weft end caught by the hook. In the course of each loom cycle, i.e. between one pick and the next, and during which there occurs a complete rotation of the main shaft 5, point A follows the closed curve 24 shown in FIG. 2. The corresponding positions of the main shaft 5 are marked on the curve 24 in degrees of arc. The various phases of the loom cycle, and in particular of the motion of the tuck-in needles, may thus be identified with the angular position of the main loom shaft.

At 40° to 50° of the loom cycle relative to a 0° position of the main shaft, for which the corresponding position of the hook 22 is labeled 0°/360° in FIG. 2, the needle 23 is in its inner inoperative position of rest at the bottom of FIG. 2, which position for the needle is identified by the reference character 23a. As the shaft 5 rotates past 50° of its cycle the needle moves horizontally from the position 23a along the curve 24, this motion appearing as an upward motion in the plan view of FIG. 2. At 120° of the loom cycle the needle moves to the left in FIG. 2, and until 140° it moves in the direction of the warp threads 25 towards the rear of the loom (i.e. towards the warp beam 17 of FIG. 1). During this movement the needle presses upwardly against the warp threads of the lower shed which are immediately above it, the shed being open. This movement brings the needle 23 into position ready to pass into the shed 88 (FIG. 7).

Between 140° and 150°, the needle turns again into a path substantially parallel to the weft threads 10 and passes into the shed 88. At 190° the hook 22 passes out of the shed 88 at the edge thereof. At the same time it turns to the right (i.e. towards the front of the loom) and moves, partly in the direction of the warp threads 25 and partly in the direction of the weft, into the yarn-receiving position shown for it in FIG. 4, where the arm is stationary, the drive shaft 5 being now at 250°. This position of the needle is identified by reference character 23b.

The end 26 of the weft 10 just picked is held taut by a selvage thread clamp 27 described in detail below. This clamp moves towards the front of the loom (cloth end) as indicated by arrow 29 from a position 27b therefor (FIG. 4) to a position 27c (FIG. 5), in which the weft end 26 is drawn over the hook 22 of the tuck-in needle. Meanwhile, the needle 23 (i.e. its hook 22) accelerates from its stationary outermost position shown in FIG. 4 and pivots back into the shed, substantially parallel to the weft. The selvage thread clamp 27 then moves on to a reversing or forwardmost position 27d (indicated in FIG. 5) corresponding to an angular position 300° for the shaft 5.

At about 280° of the loom cycle, when the hook has returned into the shed as shown in FIG. 5, the needle is temporarily retarded, retardation beginning at approximately the position shown for needle at 23c in FIG. 5. The needle stops in the position 23d (FIG. 6), i.e. its pivotal movement is interrupted. This stoppage last until

310°. The intermediate stationary position 23d leaves the hook 22 within the region of the selvage 31 (FIGS. 2, 6), whose width is equal to the length of the weft end 26 to be tucked in and which generally includes twice as many wefts as the ground 30 of the cloth.

Meanwhile the thread clamp 27 is moving back to the left as indicated by an arrow 29a in FIG. 6, towards the rear or warp end of the loom.

As the driving shaft turns past 310°, the needle 23 is re-accelerated and passes through the positions at 330°, 340°, 350° and 360° (FIG. 2) back into the inoperative stationary position 23a, in which the needle 23 is forward of the fell 40 at which the reed 8 beats up the weft. This movement of the needle 23 is repeated in each cycle of the loom.

The movement of the tuck-in needle is produced by the means described below.

Each of the selvage tuck-in devices 16 and 21 includes a cam 34 which is attached to a shaft 33 (FIG. 7) driven at the speed of the shaft 5. This cam produces a translatory movement of the needle 23 of its tuck-in device in directions parallel to the length of the warp. A follower roller 35, running on the cam 34, is mounted on a lever 37 pivoted at 36 and biased counterclockwise in FIG. 2 by a compression spring 50. This lever has a forked end 38 in which there engages a peg 39 attached to a carriage 41, which is mounted in guides to move backwards and forwards, parallel to the warps, as indicated by an arrow 42 (FIGS. 7, 8). Cam 34 thus effects translational movement of the carriage 41, and thereby of the needle.

Two levers 44 and 45 are fixed to a vertical pin 43 journaled in the carriage 41. The selvage tuck-in needle 23 is attached to the arm 44. A block 46 pivoted to the arm 45 runs in a slot 47 in a carriage 48, which is provided to effect the pivotal movement of the needle 23.

The carriage 48 is movable in casing 13 with respect to the pin 43 as indicated by arrow 49 (FIG. 8), transversely of the motion of carriage 41. Carriage 48 contains a second slide 51 along which moves a block 52. This block is pivoted to one end of a lever 53 which can oscillate about a stationary pivot 54. The lever 53 is biased by a tension spring 60 and carries a roller 56. This roller rolls on a cam 57, which causes the pivotal (as distinguished from translational) movement of the tuck-in needle and rotates at the speed of the driving shaft 5.

Two further cams 61 and 62 (FIG. 7) are also attached to the shaft 33. These cams produce the movement of the selvage thread clamp 27 and cooperate with follower levers 63 and 64 biased counterclockwise in FIG. 7 by compression springs 101 and 102. The lever 63 pivots at 65, the lever 64 at 66. The lever 63 carries a guide 68, pivoted to lever 63 at 67, for a rod 71 pivoted at 69 on the lever 64. The selvage thread clamp 27 is attached to the end of the rod 71 at the left in FIG. 7.

The elements 61, 63 and 68 cause the clamp 27 to move vertically in FIG. 7 and also in the loom in FIG. 1 (as indicated by an arrow 103), whereas the elements 62 and 64 caused it to carry out the horizontal movements described in connection with FIGS. 4 to 6 and indicated by the arrows 29 and 29a in FIGS. 4 and 6. The vertical and horizontal movements are superimposed on each other.

The development 81 of the pivoting cam 57 is represented in FIG. 9. This cam produces the pivoting movement of the tuck-in needle 23 (arrow 82 in FIG. 8) causing the actual tucking in of the weft end 27.

Operation is as follows. During operation, the pivoting cam 57 and therefore the development 81 of its profile progress in the direction of arrow 83 (FIG. 9), so that the roller 56 comes on to the upward slope 84 (FIG. 8). The lever 53 hence rotates clockwise in FIG. 8, the carriage 48 is pulled downwards (as seen in the figure), and the lever 44 pivots clockwise, the block 46 moving to the right along its slot 47. This brings the needle 23 gradually

out of its inoperative position 23a into the position which it occupies at 120° of the loom cycle (FIG. 2).

The low portion 85 of the "translatory" cam 34 now moves under the roller 35, so that the "translatory" carriage 41 and pivot 43 move to the left in FIGS. 7 and 8. The tuck-in needle 23 thus moves leftward in FIG. 2 to the positions for 130°, 140°. In this region the needle 23 presses upwards on to the lower shed warp threads 25a (FIG. 7). The threads 25a which are over the tuck-in needle at this moment are slightly raised thereby.

As the arm 44 pivots further, the needle moves to the positions for 150°, 160°, 190° (FIG. 2). In this region it passes through the shed 88.

When the lobe 89 of the "translatory" cam 34 becomes effective, the carriage 41 and needle 23 move back to the right in FIGS. 7 and 8. The needle 23, pivoting out of the shed, therefore also moves forwardly and takes up the yarn-receiving stationary position 23b at 250° (FIGS. 2 and 4).

During the subsequent tucking-in movement (the arms 44, 45 rotating counterclockwise in FIG. 8), first the downward slope 105 of the pivoting cam 57 comes into effect, accelerating the needle 23 and moving it into the shed 88. The pivotal movement of the needle is then retarded until the portion 92 of the cam 57, between 300° and 310°, comes beneath the roller 56. Portion 92 is circular. In this interval, therefore, the pivoting of the elements 53, 44 and 45, and therefore of the needle, is interrupted. Since the circular lobe 93 of the "translatory" cam 34 takes effect from about 295° onwards, the movement of the carriage 41 and pivot 43 is interrupted at the same time as the needle is in its intermediate stationary position at 300° to 310°, i.e. the translatory movement of the needle 23 is also interrupted and the needle stops completely.

The low portion 95 of the pivoting cam 57 now comes beneath the roller 56, so that the pivotal movement of the levers 53 and 44, 45 continues and the needle 23 is reaccelerated. Finally, the needle returns to the inoperative position 23a in FIG. 2. The cycle is now repeated.

In each of the diagrams of FIGS. 10 to 13, the angular position of the driving shaft 5 is shown on the abscissa. The ordinate in FIG. 10 gives the position of the needle frames 9, that in FIG. 11 the position of the reed 8, that in FIG. 12 the pivoting speed or angular velocity of the needle 23, produced by the cam 57, and that in FIG. 13 the corresponding acceleration. During the beating up movement of the reed at 50° (curve C in FIG. 11) the shed is opened as shown by the two curves D, E in FIG. 10. Between 105° and about 290°, the shed is open and the next weft is picked into the shed 88. At 245° the heddle frames 9 begin to change shed and the shed is gradually closed, the shed closing fully at 20° in the next revolution of the main shaft. Of course the invention is not limited to these particular phases for the closing of the shed.

As the speed curve F in FIG. 12 shows, the inoperative stationary position 23a is between 40° and 50° of the loom cycle. The speed between positions 23a of FIG. 2 and 23 of FIG. 4 is plotted as negative, representing clockwise rotation of the needle as seen in FIGS. 2 to 6. At 250° the speed is zero again. In the course of the counterclockwise rotation from position 23b (FIG. 4, hook 22 outside the shed) to position 23a (inner rest position, FIG. 2) the angular velocity or speed, which must be positive for such rotation, becomes temporarily zero between points R (300°) and S (310°), and it then reverts to a positive value until the needle 23 has returned to position 23a. It will be seen from FIG. 2 that during the phase of the loom cycle extending between 300° and 310°, the hook 22 is, crosswise of the loom, between the inner and outer edges of the selvage 31. Vertically it is inside the shed, i.e. between the upper and lower halves 25b and 25a of the shed shown in FIG. 7.

The acceleration curve G in FIG. 13, accordingly, gives

first a positive acceleration Z after the 250° position, then a negative acceleration before point T (i.e. a retardation W), then zero acceleration between points T and U, and a positive acceleration X after point U. The acceleration is negative at W notwithstanding the positive value of the associated speed, which this negative acceleration is in the process of reducing in absolute magnitude.

As FIG. 10 shows, the distance between the warp threads 25a and 25b (FIG. 7) moving from the upper and lower shed positions towards the center is already somewhat reduced at 310°, so that the weft end 26 on the hook 22 is held by the warp threads on both sides of it and cannot spring back out of the needle. As the elements of the loom move on after the 310° position, the heddle frames move further towards the closed shed position, which is finally reached at 20° after the start of the next cycle. The weft end 26 leaves the hook 22 and is bound in by the warp threads. After the shed opens again, the reed 8 beats up both the tucked-in end of the last weft but one, and the weft just picked. Another weft is then picked, and so on.

The acceleration curve of FIG. 13 therefore shows that when the hook 22 starts to return, at 250° of the loom cycle, from its extreme outermost position shown on curve 24 in FIG. 2, the hook first suffers positive acceleration over an interval of time Z, reaching at the end of that time, i.e. at about 275°, a counterclockwise or positive angular velocity indicated at L in FIG. 12. In the particular exemplary operation illustrated, as soon as the acceleration falls to zero at the end of interval Z, it passes to a negative value, so that the hook on entering the shed is decelerated over a time interval W terminating at 300°, by which time the hook has been reduced to zero angular velocity, as indicated at R in FIG. 12. The hook is held at rest between 300° and 310°, with zero angular velocity and zero angular acceleration. It then suffers a positive acceleration over a time interval X, acquiring a substantially uniform, counterclockwise or positive angular velocity M (FIG. 12) which is maintained until above 10° of the next cycle. Then the needle is braked, i.e. undergoes negative acceleration, as appears at the left end of FIG. 13, to reduce its velocity to zero at 40°.

In another embodiment, the speed, as indicated by the broken-line curve K in FIG. 12, does not drop to zero between 300° and 310°, and the acceleration curve in FIG. 13 moves from the negative portion W' shown by broken lines directly into a positive portion X'. In this case therefore, the tuck-in needle 23 is only braked, and is not brought to a complete stop. This still gives the desired effect, i.e. the weft end 26 is still held better by the warp threads 25a and 25b which are in process of closing the shed.

The interruption or braking of the tucking-in movement of the needle 23, instead of extending over 10° of the rotation of the driving shaft, may extend over a different range, for example 5° or 15°. Also, it may for example occur between 290° and 300°. The range in which the needle 23 is temporarily retarded or stopped, and then re-accelerated depends on the operational conditions, more particularly on the length of the weft ends 26 which are to be tucked in, i.e. on the width of the selvage 31. The intermediate retardation or stopping of the needle 23 must in any case take place within the selvage 31, so that the weft end 26 is still being held by the hook 22.

In a loom with a single web of cloth and a continuous cloth beam, the tuck-in device 21 for the dividing selvage (FIG. 1) is unnecessary. Tuck-in needles 23 need only be provided in the tuck-in devices 16 at the edges of the cloth.

While the invention has been described hereinabove in terms of a presently preferred mode of practice of the method thereof and in terms of a number of presently preferred embodiments of the apparatus thereof, the invention itself is not limited thereto but includes all modi-

ifications on and departures from the practice and embodiments hereinabove described properly falling within the spirit and scope of the appended claims.

I claim:

1. In the weaving of cloth from warp and weft threads on a cyclically operating loom in which the warp threads are formed into successive sheds and in which each weft thread is picked through a shed from a supply bobbin remaining outside the shed on one side thereof and is cut off on that one side of the shed to provide a weft thread having ends extending beyond the shed on each side thereof, a method of tucking in at least one of said ends of each weft thread to form a selvage which comprises accelerating the tip of a tuck-in needle toward the shed from a position of rest outside the shed on one side thereof, grasping said end of the weft thread with the tip of the needle in the course of return of the tip toward the shed, decelerating the needle while the tip

thereof is in the portion of the shed corresponding to the selvage portion of the width of the cloth, and reaccelerating the needle toward an inner position of rest.

2. A method according to claim 1 wherein said deceleration is continued to bring the needle tip to rest with the tip thereof grasping the weft end in the said portion of the shed.

3. A method according to claim 2 including the further step of holding the needle stationary for a fraction of the loom cycle between said decelerating and reaccelerating steps.
